Specification for Design.

Patented June 17, 1913.

Application filed March 14, 1913. Serial No. 754,393. Term of patent 7 years.

To all whom it may concern:

Be it known that I, FRANK J. SHAW, a citizen of the United States, and resident of Leominster, in the county of Worcester, State of Massachusetts, have invented a new, original, and ornamental Design for Vehicle-Tops, of which the following description, in connection with the accompanying drawings, is a specification.

Figure 1 is a front elevation of a vehicle top showing my new design; and Fig. 2 is a side elevation of the top shown in Fig. 1.

I claim:

The ornamental design for a vehicle top, as shown.

I have signed my name to this specification in the presence of two subscribing witnesses.

FRANK J. SHAW.
